ADJUSTABLE GRILLE

James P. Burcham, Indianapolis, Ind.

Application March 13, 1933, Serial No. 660,520

5 Claims. (Cl. 20—71)

This invention relates to a grille for serving as a guard or protection in connection with windows and similar openings, door screens and the like, and particularly wherein said grille is adjustable within limits as to the length and width thereof.

The principal object of this invention is to economically produce a grille of the above character, durable and with sufficient strength to 10 withstand impact with a substantial margin for safety.

One feature of the invention resides in the form and construction of the fabricated body of the grille to give it the desired strength and 15 appearance of sturdiness, but principally to facilitate the relative movement of the members in the extension or collapsing thereof during adjustment.

Another feature of the invention resides in 20 the form of construction of the expandible frame members for providing a frame adapted to support and hold the fabricated body anchored therein while permitting relative movement for adjustment thereof.

25 The full nature of the invention will be understood from the accompanying drawing and the following description and claims:

In the drawing, Fig. 1 is a plan view of a grille with portions broken away. Fig. 2 is a section 30 taken on the line 2—2 of Fig. 1. Fig. 3 is a section taken on the line 3—3 of Fig. 1.

In the drawing there is shown a grille having a rectangular frame comprising the outer channel members 10 and the inner channel members 35 11 slidable therein. At the four corners of the frame, the ends of the outer channel members 10 embrace and are riveted to the adjacent ends of the inner channel members 11, the rivets 12 being hollow and cylindrical in shape and extending intermediate the channel members. Extending from opposite ends of the frame there 40 are ears 13 formed integral with the respective members 10 and 11. Thus, the telescoping frame members may slide relative to each other so as to permit the frame to be extended or contracted, both longitudinally and laterally thereof.

The body portion of the grille comprises a plurality of interlaced metal strips 14 and 15. Said metal strips are of substantial width as compared with their thickness and are woven crosswise of each other so as to extend over and under alternate cross strips. Said strips are strengthened by stamping reverse beads 16 and 17 thereon, the beads 16 bulging from one side, 55 while the beads 17 bulge from the opposite side.

Intermediate each successive pair of said beads there is stamped a "rivet head" in the form of a bulge 18 at the point of intersection of the cross strips. The "rivet head" projections 18 extend from opposite sides of the respective strips 14 and 15 at their point of crossing with the flat or non-bulged surfaces lying adjacent each other. This gives the appearance from either side of the grille that the strips are riveted together at their point of intersection, while at the same time permitting their pivotal movement relative to each other when the grille is extended or contracted.

The free ends of the bars extend into the frame members through a slot 19 formed by bending 70 inwardly the inner surfaces 20 and 21 of said members. Said slot is only slightly wider than the thickness of the bars so as to permit free sliding movement of the bars therein. Adjacent each of the free ends of said bars there is formed 75 a ball and socket, the spherical projection being indicated at 22 and the spherical socket being indicated as 23, the ball and socket nesting in each other so as to provide a pivotal bearing and anchor for the adjacent free ends of the bars. 80 The shoulders formed on the bars by the ball and socket formation are adapted to lock the same within the channel members so as to prevent their escape while permitting of their free sliding movement therein. The said projections 22 and 23 are formed on one set of alternate bars, to 85 extend in opposite directions to those on the other set of alternate bars in order that the grille may be balanced in relation to the frame.

At each corner of the frame the bar extending 90 therein is provided with a hook 24 adapted to extend around and pivotally lock with the rivet 12 so that the grille is firmly but pivotally anchored therein.

By means of this construction, when the frame 95 is extended longitudinally thereof, it will contract laterally and when contracted longitudinally, will be extended laterally. Thus, the frame, within limits, may be adjusted to different sized openings and be secured in place by means of 100 the ears 13. In the extending and contracting movement, the channel members 11 slide in the channel members 10. During such movement, the grille members 14 and 15 move relative to each other at different angles, pivoting about 105 their ball and socket connections within the frame members and freely moving as about a pivot with respect to each other at their points of intersections indicated by the "rivet heads" 18. The grille cannot escape from the frame and will 110

at all times be maintained in proper relation therewith through the pivotal connections at the corners and the confinement of their free ends in the hollow channel members.

5 The invention claimed is:

1. A grille comprising a rectangular frame having a plurality of frame members telescoping and slidable one within the other, each of said frame members having a slot formed longitudinally

10 thereof and centrally of its sides, and a plurality of interwoven grille bars having their free ends extending through said slot and bent in opposite directions within said members for slidably interlocking said free ends therein.

15 2. A grille comprising a rectangular frame having a plurality of frame members telescoping and slidable one within the other, each of said frame members having a longitudinal opening formed therein, means for securing the adjacent mem-

20 bers to each other at each corner of the frame, a plurality of interwoven grille bars having their free ends extending through said slot, means for anchoring the free ends of certain of said bars to said frame members for locking the grille

25 therein, and a hook formed on the end of such of said bars as extend into the corners of the frame for embracing said securing means to anchor said grille therein.

3. A grille comprising a rectangular frame hav-

30

ing a plurality of hollow frame members of rectangular cross section, said frame members telescoping and being slidable one within the other and each provided with a slot extending longitudinally thereof on its inner side centrally of its lateral sides, and a plurality of interwoven grille bars having their free ends extending through said slot and bent in opposite directions within said members for slidably interlocking said free ends therein.

80 4. A grille comprising a rectangular frame having a plurality of frame members telescoping one within the other, and each of said frame members having a slot formed longitudinally thereon on its inner side, a plurality of interwoven grille bars having their free ends extending through said slot, and a ball and socket formation adjacent said free ends for providing an interlocking pivotal bearing between the contacting ends of said bars.

85 5. In a grille, a plurality of interwoven grille bars provided with reversely extending beads formed substantially throughout the length thereof, downwardly extending "rivet head" formations on said bars at substantially their point of intersection, and ball and socket formations adjacent their free ends for providing a pivotal interlocking bearing.
